UNITED STATES PATENT OFFICE.

ALBERT M. HOPPER AND JAMES O. HOPPER, OF PITTSBURG, KANSAS.

MEANS FOR AUTOMATICALLY OPENING MINE-DOORS.

1,242,190.

Specification of Letters Patent.

Patented Oct. 9, 1917.

Application filed July 5, 1917. Serial No. 178,809.

To all whom it may concern:

Be it known that we, ALBERT M. HOPPER and JAMES O. HOPPER, citizens of the United States, residing at Pittsburg, in the county 5 of Crawford and State of Kansas, have invented certain new and useful Improvements in Means for Automatically Opening Mine-Doors, of which the following is a specification, reference being had to the accompanying drawings.

This invention relates to means for operating mine doors, and particularly to means of this character designed to be automatically operated by an approaching car.

15 The general object of the invention is to provide a very simple and effective apparatus to this end, so constructed that the doors will be shifted to an open position by the first car of the train and then held open 20 by succeeding cars, the door automatically closing as soon as the train has passed.

A further object is to provide oppositely disposed weights on the operating shaft which will counterbalance each other, the 25 weight arms, however, being loosely connected to the shaft to prevent contact with the ground from breaking the arms.

A further object is to provide very simple 30 means for transmitting the motion of the operating shafts to the doors, and in this connection to provide means for cushioning the shock incident to the striking of the actuating dog by a car.

A further object is to provide means 35 whereby the doors may be independently opened and closed, without actuating or shifting the automatic mechanism.

Other objects will appear in the course of the following description.

40 My invention is illustrated in the accompanying drawings, wherein:—

Figure 1 is a top plan view of our invention, the doors being shown in section;

Fig. 2 is a longitudinal sectional view of 45 the construction illustrated in Fig. 1;

Fig. 3 is a perspective view of one of the doors in its open position;

Fig. 4 is a perspective view of one of the plates 27;

50 Fig. 5 is a fragmentary sectional view through the shaft 14 and the rod 48;

Fig. 6 is a like view to Fig. 5, but showing the connection of the arm 49 to the shaft;

Fig. 7 is a side elevation of the connecting 55 rod 30.

Referring to these drawings, 10 designates the door frame, which may be of any suitable construction, and 11 indicates each door. These doors are connected to the 60 door frame by the hinges 12, which may be of any suitable construction. Ordinarily the doors, when closed, stand at an angle of 60° with relation to each other. The door frame extends across the rails 13, which 65 rails are supported on ties, as usual.

Disposed in advance of the doors is a shaft 14, extending beneath the rails, this shaft being supported in brackets 15 carried on yokes 16 mounted upon the adjacent ties. 70 The shaft 14 at its inner end is provided with an upwardly extending arm 17, which I will hereafter term a dog, this arm normally extending upward and slightly away from the door. Disposed adjacent the 75 door is a rock shaft 18, which is mounted in suitable bearings carried by the yokes 19, the shaft being disposed below the rails 13 and being provided with an upwardly extending arm 20 and is connected thereto by 80 a connecting rod 21, pivoted to the ends of the arms. This connecting rod is about thirty feet in length or may be of any other desired length. Mounted upon the shaft 14 is the downwardly and forwardly extending 85 arm 22, from which extends a link 23, which is slidingly engaged with an elongated loop 24 formed upon an operating rod 25.

Attached to the bottom of each door 11, adjacent the hinged portion thereof, is a 90 plate 26 disposed horizontally and extending inward toward the track, but below the level of the same, this plate having an upwardly extending flange 27, which is bolted or otherwise attached to the door. The rod 95 25 is connected to the plate 26 on the corresponding door. The plate 26 is approximately triangular. The rod 25 is pivotally connected to one corner of the plate, as at 28, and transversely opposite to the hinged 100 connection of the door. At the forward corner of this plate 14 is pivotally connected a transversely extending rod 29, formed in two sections, this rod being connected to the rear corner of the opposite plate 26. From 105 the rear corner of the first named plate 26 extends a connecting rod 30, also formed in two sections, this connecting rod crossing

the connecting rod 29 and being connected to the forward corner of the second named plate 26, the middle portion of the connecting rod 30 being downwardly bent, as at 31, 5 to pass beneath the rod 29.

As before stated, each of the rods 29 and 30 is formed in two sections. Each of these sections is provided with upwardly extending lug 32, while the other section extends 10 through these lug. Coiled springs 33 resist longitudinal movement of the sections upon each other and cushions the doors when they are opened by the car striking the dog 17 of the corresponding dog on the sides of the 15 doors, as will be later explained. The shaft 14 projects on the lefthand side of the track and disposed on the rear side of the doors is a corresponding shaft 34, which is mounted in yokes 35 carried by the ties, this shaft 20 being provided with the upwardly projecting arm 36 and pivotally connected to this arm 36 is a longitudinally extending rod 37, corresponding to the rod 31, which in turn 25 is connected to an arm 38 mounted upon a rock shaft 39 and corresponding to the rock shaft 18 heretofore described.

Extending downward from this shaft 34 is an arm 40 and pivotally connected to this arm is a longitudinally extending rod 41, 30 which at one end engages with a lever 42 pivotally mounted upon a longitudinally supporting tie 43 and having a pin 44 at its opposite end which engages in the longitudinally extending loop 45 formed upon the 35 end of a rod 46, which corresponds to the rod 25 and is pivotally connected to the plate 26^a. A spring 47 urges the rod 46 in a direction to hold both doors 11 closed so that the pin 44 is disposed at the forward 40 end of the loop 45.

Mounted upon the rock shaft 14 are the oppositely extending arms 48 and 49, each of which carry adjustable weights 50. The arms are of the same length and the weights 45 balance each other. Preferably there is a certain relative movement of the shaft 14 and the arms 48 and 49, this being accomplished by forming a groove 51 on the inner face of the arm surrounding the shaft, this 50 groove extending forward and downward and providing a pin 52 on the shaft which engages in this groove. The arm 49 is also provided with a corresponding groove 51^a, which is disposed oppositely to the groove 51 and the shaft is provided with a pin 52^a which engages in this groove. Thus when the dog 17 is struck and shifted in a clockwise direction by the first car of a train, the arm 48 will be lifted. The arm 49 will be 55 depressed but when the weight strikes the ground, as it will almost immediately, the arm 49 becomes inactive. After the train has passed the rod 21, however, the arm 48 carries the shaft 14 back to its normal position 60 until it is counterbalanced by the lift- 65

ing of the arm 49 when the rotation of the shaft will stop. This construction prevents the too great rotation of the shaft in a counterclockwise direction. As before stated, the dog 17 extends upward and away 70 from the doors 11 and if any heavy piece of rock or ore should fall upon this dog 17 or upon the rod 21, the shaft 14 will rotate in a counterclockwise direction, but as soon as the arm 48 strikes the ground, it will stop 75 rotating but the shaft will continue lifting the arm 49. As soon as the rock has rolled off of the dog 17, the arm 49 will bring the shaft back to its normal position again.

The counterclockwise rotation of the shaft 80 14 from its normal position will not affect the rod 25 inasmuch as the link 23 has sliding engagement with the loop 24. The shaft 34 is also provided with oppositely disposed arms 53 and 54 having weights 55 and the 85 arms are connected to the shaft 34 in the same manner as are the arms 48 and 49 and to the same end.

It will be seen that the doors may be manually opened without rotating the shafts 14 90 or 34 because of the loose connection between the link 23 and the loop 24 and between the lever 42 and the loop 45.

The operation of this invention will be obvious and is as follows:—A train advancing toward the doors 11 will strike the dog 17 and shift the dog over, rotating the shaft 14 in a clockwise direction and through the rod 35 and the plates 26 and 26^a opening the doors. The doors will be held 100 open by the engagement of the several cars of the train with the rod 21 until the last car has passed through the door. As soon as the last car has passed, however, the counter-weighted arm 48 will act to rotate the 105 parts to their initial position ready for the next train. The train coming from the opposite direction will, of course, first operate the dog 36 which will shift the doors to an open position and the cars engaging with 110 the rod 37 will hold the doors open until the last car has passed, whereupon the doors will be closed by the spring 47. The rotation of the shaft 34 will be resisted by the counter-weighted arm 54 and this counter-weight will act to return the shaft 34 to its initial position ready for another operation.

While we have illustrated a form of our invention which we believe to be thoroughly practical, yet it is obvious that many minor 120 modifications may be made, without departing from the spirit of the invention.

Having described our invention, what we claim is:—

1. The combination with a pair of hinged 12 mine doors, of car actuated door operating means including rock shafts disposed on opposite sides of the doors and having each an upwardly extending car engaging dog and having each a downwardly extending 13

- arm, members attached to each door and extending therefrom, rods operatively connecting the downwardly extending arms of each rock shaft to a corresponding member, 5 a pair of crossed rods connecting said members, each of said cross bars being formed in two sections having sliding engagement with each other, and a spring resisting sliding movement of the rods.
- 10 2. The combination with a pair of hinged mine doors opening in the same direction, of car actuated door operating means including rock shafts disposed on opposite sides of the doors and each having a car engaging dog 15 and a radially extending arm, members attached to each door and extending inward therefrom, rods operatively connecting the radially extending arms of each rock shaft to a corresponding member, and a pair of 20 cross rods connecting said members, each of said rods being formed in two sections, one of said sections having a pair of perforated lugs, the other section extending through said perforations and having a stop 25 disposed between the lugs, and springs disposed on each side of the stop and between said stop and the lugs.
3. The combination with a pair of hinged mine doors opening in the same direction, of 30 car actuated door operating means, including rock shafts disposed on opposite sides of the doors and each having a car engaging dog and each having a radially extending arm, members attached to each door and 35 extending inward therefrom, rods operatively connecting the radially extending arms of each rock shaft to a corresponding member, a pair of crossed rods connecting said members, each of said rods being 40 formed in two sections yieldingly resisting sliding movement of the sections upon each other.
4. The combination with a pair of hinged mine doors, of car actuated door operating 45 means including rock shafts disposed on opposite sides of the doors and having each an upwardly extending car engaging dog and having each a downwardly extending arm, members attached to each door and extending inward therefrom, rods operatively connecting the downwardly extending arms of 50 each rock shaft to a corresponding member, a pair of crossed rods connecting said members, means for returning said rock shafts to a normal position with the dogs extending upward and toward the doors, and comprising oppositely disposed weighted arms on each rock shaft, each of said arms being engaged by the rock shaft upon a movement 55
- of the rock shaft in one direction, the rock 60 shaft having a movement independent of said arms upon a movement in the opposite direction.
5. The combination with a pair of hinged mine doors, of car actuated door operating 65 means including rock shafts disposed on opposite sides of the doors and having each an upwardly extending car engaging dog and having each a downwardly extending arm, members attached to each door and extending inward therefrom, rods operatively connecting the downwardly extending arms of each rock shaft to a corresponding member, a pair of crossed rods connecting said members, means for returning said rock 70 shafts to a normal position with the dogs extending upward and toward the doors and comprising oppositely disposed weighted arms on each rock shaft, each of said arms at its inner end surrounding the shaft and 75 being loosely mounted thereon, each arm being formed with a circumferentially extending recess, and pins on the shaft extending into said recesses.
6. The combination with a track, a door 80 frame extending across the track and a pair of doors hinged to said frame, of means for operating the doors including transversely extending rock shafts mounted below the track on each side of the doors, each of said 85 rock shafts having an upwardly extending car actuated dog and a downwardly extending arm, oppositely disposed weighted arms mounted upon each rock shaft, plates attached to the lower ends of the doors and 90 having inwardly projecting portions, oppositely extending rods connected one to each plate and having elongated loops at their other ends, a link connecting the downwardly extending arm of one rock shaft to 95 the corresponding loop and having sliding engagement with said loop, a connecting rod extending from the other door and formed with an elongated loop, a lever having a pin extending into said loop, a rod connecting 100 the other end of the lever with the downwardly extending arm of the corresponding rock shaft, and a spring urging said doors to a closed position.
- In testimony whereof we hereunto affix 110 our signatures in the presence of two witnesses.

ALBERT M. HOPPER.
